UNITED STATES PATENT OFFICE.

HARRY L. BRADLEY, OF MILWAUKEE, WISCONSIN.

ELECTRIC-CURRENT CONTROLLER.

1,817,772.

Specification of Letters Patent.

Patented Oct. 7, 1919.

Application filed May 3, 1916. Serial No. 95,030.

To all whom it may concern:

Be it known that I, HARRY L. BRADLEY, a citizen of the United States, residing at Milwaukee, in the county of Milwaukee and State of Wisconsin, have invented certain new and useful Improvements in Electric-Current Controllers, of which the following is a specification, reference being had to the accompanying drawings, forming a part thereof.

This invention relates to improvements in electrical current controlling devices employing variable contact resistance mediums or members composed of elements in the form of plates, disks or comminuted material, the resistance of said mediums or members being varied by pressure, of the class disclosed in United States Patents No. 728,817, dated March 31, 1903, and No. 1,120,018, dated December 8, 1914, and in the pending application of Lynde Bradley Serial No. 813,665, filed January 22, 1914.

In the construction of controllers of the type referred to it has been customary to arrange the mechanism in such a manner that the pressure would be applied and released at one end only of the resistance medium or members, and as each plate forming an element of the resistance medium, or, in the case of comminuted material the medium as a whole, is always in frictional contact with the container or supporting means, the elements or material nearest the point at which the pressure is applied will be subjected to the greatest variations in pressure, and these variations will decrease as the frictional resistance to pressure changes will be increased as the distance from the point of application of pressure increases. This is undesirable, as the elements or material subject to the greatest pressure variations are also subject to the greatest variations of contact resistance, and therefore perform greater service in the nature of current control than their more passive neighbors, the result being that such elements or material are subjected to greater mechanical wear, heat and electrical stress than the elements or material at the ends of the resistance members remote from the point of application of pressure, and the tendency to deterioration from use is unbalanced, being greater at the pressure-applying end.

Rheostatic controllers of this type having compressible resistance members have been provided with frames and mechanism sup-

porting means of greater weight and strength than those generally employed in the step by step form of controllers having the wire coil or grid type of resistance members. This has been necessary in order to withstand the mechanical stresses occurring when the mechanism was operated to compress the resistance members. Lightness and small dimensions are of great importance in many instances where this class of apparatus is used, for example, in the control of small portable electric hoists, air compressors, drills, grinders, etc.

For this reason the increased weight of the compression type of controllers is also undesirable.

The main objects of the present invention are, first, to provide means by which pressure can be applied simultaneously at both ends of the resistance members, thus enabling the elements or material at both ends of the members to operate with maximum pressure variations, and second, to so construct an electric current controller of this type that the framework supporting the mechanism and resistance members need not be of any greater weight and strength than that used in connection with the wire coil and grid form of resistance members.

In the accompanying drawings like characters designate the same parts in the several figures.

Figure 1 is a side elevation of an electric current controller embodying the invention; Fig. 2 is a plan view of the same; Fig. 3 is a longitudinal section on the line 3—3, Fig. 2, parts being broken away; Fig. 4 is a cross section on the line 4—4, Figs. 1 and 2; Fig. 5 is a wiring diagram of the controller in connection with an alternating current induction motor of the squirrel cage type; and Fig. 6 is a similar diagram of the controller in connection with a non-reversible direct current motor.

Referring to Figs. 1 to 4, inclusive, showing the controller in its off or normal state, the framework comprises a U-shaped metal plate or main section 1, to which is attached crosswise thereof, a U-shaped bearing bracket 2. The bracket 2 is provided with bearings 3, in which a rock shaft 4 is mounted. Eccentrics 5 are mounted on the shaft 4 with their points of greatest eccentricity on diametrically opposite sides thereof, and are provided with eccentric straps 6, which are connected by rods 8 with equaliz-

ing plates or members 9. The rods 8 pass centrally and loosely through the plates or members 9, and are threaded and provided with nuts 10, between which and the plates 9 or members 9, bearing washers and springs 11 are interposed, thus forming yielding and adjustable connections between the rods 8 and said plates or members 9.

Resistance members 12, 12' and 12'', which may consist as shown in Fig. 3, of tubular casings each containing a series of disks of suitable compressible and variable resistance material such as carbon, are carried parallel with and equidistant from the eccentric rods 8 by the upturned ends of the frame section 1, and are provided at the ends with longitudinally movable plungers 13, bearing against the terminal disks of the resistance members and constituting with the equalizing plates 9, compression members. The plunger stems have flexible circuit connections 14, attached to and insulated from the frame section 1, and are provided at their outer ends with insulating knobs 15, with which the plates or members 9 engage.

Two switch drums 16, of insulating material, are mounted on the shaft 4 and are provided with segmental contact and conducting strips 17 and 17', which constantly engage with contacts 18 and 18'.

The controller is also provided with relatively fixed contacts 19, 20, 19' and 20', so arranged that the segmental contact strips 17, 17' will engage with the contacts 19 and 20 when the shaft 4 is turned in one direction, and will engage with the contacts 19' and 20' when said shaft is turned in the opposite direction. The several contacts 18, 18', 19, 19', 20 and 20' are resiliently connected by springs with insulating blocks 21 and 22, which are attached to the frame section 1, and are provided, as shown, with terminals for attachment of the circuit wires 46 with which the contacts are connected.

The shaft 4 is provided at one end with a sheave or pulley 23, around which an operating rope or cable 24 is wrapped two or more times and fastened at the center of 50 the turns, so that the shaft 4 with the eccentricities 5 and switch drums 16 may be turned in either direction from its off or normal position by pulling on one or the other end of the rope or cable.

55 A spring 25, loosely coiled around the shaft 4 and engaging at its ends with a stud 26 on the sheave 23, and with a fixed stud 27, attached to the frame, tends to return the shaft 4 with the eccentricities 5 and switch drums, to its off or normal position.

In the operation of the controller, when the eccentricities 5 are turned with the shaft 4 in either direction from their off or normal position, in which they are shown in Fig. 3, the equalizing plates or members 9

will be drawn simultaneously toward each other, and by engagement with the irregular knobs 15 at the outer ends of the plungers 13, will force the plungers at opposite ends of the resistance members 12, 12' and 12'' to equally toward each other, thereby gradually and equally compressing the resistance elements or medium from both ends of the several members, each equalizing plate 9 and plunger 13 acting and reacting against the opposing equalizing plate and plunger throughout the entire length of the intervening resistance member or medium, and the pressure exerted upon the ends of the several members being equally distributed by reason of the loose yielding connections of the equalizing plates or members 9 with the eccentric rods 8. By turning the sheave 23 the electric circuit or circuits through the controller are closed and opened or commuted, and the resistance is compressed and relieved of compression.

In connection with a squirrel cage induction motor, as shown in Fig. 5, the circuit connections of the controller are as follows:

Assuming that the sheave 23 is turned clockwise to bring the contact strips or plates 17 and 17' into initial engagement with the contacts 19' and 20', the circuits for the several phases of current are as follows:

For phase A, starting in line 28, the circuit is through the resistance member 12', conductor 29, contact 18', contact plate 17', contact 20' and conductor 30, to the motor; thence through conductor 31, contact 19', contact plate 17, contact 18, conductor 32 and resistance member 12'' to line 33.

For phase B, starting with line 33, the circuit is through resistance member 12', conductor 29, contact 18', contact plate 17', contact 20' and conductor 30 to the motor; thence through conductor 34 and resistance member 12 to line 35.

For phase C, starting with line 35, the circuit is through resistance member 12 and conductor 34, to the motor; thence through conductor 31, contact 19', contact plate 17, contact 18, conductor 32 and resistance member 12'', to line 33.

By turning the sheave 23 further from its normal or central position in a clockwise direction, the resistance elements or medium of the members 12, 12' and 12'' are subjected to greater compression, the degree of compression depending on the extent of angular movement of the sheave with the eccentricities 5 and the resistance to the passage of the current being correspondingly reduced.

At the limit of the angular movement of the sheave 23 with the eccentricities 5 from the normal or central position, the resistance members are subjected to maximum compression, and offer practically no resistance to the passage of the current, which is sup-

plied at full potential to the motor, and operates the same at full speed.

By turning the sheave 23 in a counter-clockwise direction from its normal or central position, the compression mechanism operates in the manner hereinbefore described to subject the resistance members 12, 12' and 12" at both ends to equal and gradually increasing pressure, but the circuit 10 connections leading to the motor are shifted by the contact plates 17 and 17' and the contacts 18, 18', 19 and 20, to change the relationship of the phases of the current so as to reverse the direction of rotation of 15 the motor.

Turning the sheave 23 back in either direction to its normal or central position operates first, to release the resistance elements or medium from compression, and then to 20 open the motor circuit at the contacts 19' and 20' or 19 and 20.

In connection with a non-reversible direct current shunt motor as shown in Fig. 6, the resistance elements or medium are 25 compressed in like manner except in this case the sheave 23 with the eccentrics 5 and 1 switch drums 16 is turned in one direction only from its normal or central position.

By turning the sheave in a clockwise direction till initial engagement between the contact plate 17' and the contact 20' occurs, the circuit may be traced beginning with the line 36 through contact 18', contact plate 17', contact 20' and conductor 37 to the motor armature; thence through conductor 38, resistance members 12', 12 and 12" to line 39.

The field circuit is traced from the line 37 through shunt field 40, conductor 41, conductor 42, to line 39.

As the sheave 23 with the eccentrics 5 and switch drums 16 is turned further in a clockwise direction from its normal or central position, the compression of the resistance elements or medium of the members 12, 12' and 12" is gradually increased and their resistance correspondingly lowered until the switch plate 17 is brought into engagement with the contact 19, thereby short-circuiting the resistance members 50 from the conductor 38 through conductor 43, contact 19, contact plate 17, contact 18 and conductor 42, to line 39.

A reverse movement of the sheave 23 operates first, to open the short circuit at contact 19, then to relieve the resistance elements or medium of compression, and finally to open the motor circuit at the contact 20'.

Various changes in details of construction and arrangement of parts of the controller 60 may be made without departure from the principle and scope of the invention as defined in the following claims.

I claim:

1. In an electric current controller the 65 combination of a compressible resistance

medium and means comprising oppositely movable compression members for exerting pressure simultaneously in opposite directions against both ends of the resistance medium, each compression member acting 70 and reacting against the other compression member throughout the entire length of said resistance medium.

2. In an electric current controller the combination of a resistance medium whose 75 conductivity is variable by compression and means comprising oppositely movable compression members for subjecting said medium at opposite ends to variable pressure simultaneously in opposite directions, each 80 compression member acting and reacting against the opposing compression member throughout the entire length of the intervening resistance medium.

3. In an electric current controller the 85 combination of a compressible and variable resistance medium composed of a series of disks, a casing supporting and loosely confining said disks, and means comprising oppositely movable compression members 90 for subjecting said medium simultaneously to equal and variable pressure in opposite directions, each compression member acting and reacting against the opposing compression member throughout the entire series 95 of disks.

4. In an electric current controller the combination of a resistance medium whose conductivity is variable by compression, means comprising oppositely movable compression members for subjecting said medium at opposite ends simultaneously to equal pressure in opposite directions, each compression member acting and reacting throughout the entire length of the resistance medium, and means connected with and operated by the compression means for opening and closing the circuit through the resistance medium. 105

5. In an electric current controller the 110 combination of a resistance medium whose conductivity is variable by compression, means comprising oppositely movable compression members each acting against the other throughout the entire length of the 115 intervening resistance medium for subjecting said medium simultaneously at opposite ends to equal pressures in opposite directions, and means connected with and operated by the compression means for short-circuiting said medium at a certain stage of compression thereof. 120

6. In an electric current controller the combination of a plurality of parallel compressible variable resistance members and 125 means comprising oppositely movable compression members for subjecting said resistance members simultaneously at both ends to equal and variable pressure in opposite directions, each compression member acting 130

and reacting against the opposing compression member throughout the entire length of the intervening resistance member.

7. In an electric current controller the combination of a compressible resistance member, oppositely movable compression members at the ends of the resistance member, a rock shaft provided with oppositely working eccentrics, and rods connecting the eccentricities with the compression members at opposite ends of the resistance member.

8. In an electric controller the combination of a number of resistance members whose conductivity is variable by compression, equalizing members at opposite ends of the resistance members, a rock shaft provided with oppositely working eccentrics, and rods connecting the eccentrics with the equalizing members.

9. In an electric controller the combination of a compressible and variable resistance member, a rock shaft provided with oppositely working eccentrics, and compression members at the ends of the resistance member having yielding connections with the eccentrics and acting and reacting against each other throughout the entire length of the resistance member.

10. In an electric controller the combination of a number of compressible resistance members, equalizing members engaging the ends of the resistance members, a rock shaft provided with eccentrics, and rods connected with the eccentrics and having loose yielding connections with the equalizing members, for applying pressure simultaneously

to the ends of the resistance members in opposite directions.

11. In an electric current controller the combination of a frame, a resistance member mounted thereon and compressible from both ends to vary its conductivity, compression members engaging the ends of the resistance member, a rock shaft connected with said compression members so as to move them simultaneously toward each other, a segmental switch contact mounted on said shaft and switch contacts mounted on the frame and coöperating with the segmental contact to close and open the circuit through the resistance member.

12. In an electric current controller the combination of a frame, a resistance member mounted thereon and compressible from both ends to vary its conductivity, compression members engaging the ends of the resistance member, a rock shaft connected with the compression members so as to move them simultaneously toward each other, segmental switch contacts mounted on said shaft and switch contacts mounted on the frame and coöperating with the segmental contacts to close and open the circuit through the resistance member and to short-circuit said member at a certain stage in the compression thereof.

In witness whereof I hereto affix my signature in presence of two witnesses.

HARRY L. BRADLEY.
